UNITED STATES PATENT OFFICE

ALEXANDER KÜHNS, OF BERLIN-CHARLOTTENBURG, GERMANY, ASSIGNOR TO WESTINGHOUSE ELECTRIC & MANUFACTURING COMPANY, A CORPORATION OF PENNSYLVANIA

CIRCUIT INTERRUPTER

Application filed October 20, 1927, Serial No. 227,487, and in Germany October 20, 1926.

My invention relates to circuit interrupters, and more particularly to the operating mechanism therefor.

One object of my invention is to provide an operating mechanism for a circuit interrupter that shall function to rapidly separate the contacts thereof.

Another object of my invention is to provide a circuit interrupter with an operating mechanism, the initial movement of which stores energy in a biasing member which is to be expended during the latter part of the movement of the operating mechanism.

The use of contact members movably mounted on the bridging member of oil circuit interrupters, and the use of springs between the contact member and the bridging member, which are placed in tension during the opening movement of the breaker, is well known in the circuit-interrupter art.

The use of such springs for each pair of contact members has the drawback that the bridging member may not remain alined properly, so that only one of the springs is placed under tension, and so pulls out its contact member while the other contact member remains in its closed position. This may result in an arc continuing between one pair of contact members to damage their abutting surfaces, which must be repaired before the circuit interrupter can be again employed.

In order to overcome this drawback, my oil circuit interrupter is so designed that the contact members are rigidly mounted on the bridging member, and the bridging member, or the switch rod crank member, or both are connected to the actuating means through a spring.

My invention will best be understood by referring to the drawings, in which,

Figure 1 is a view, in elevation, of a particular embodiment of my invention,

Fig. 2 is a similar view of another embodiment that my invention may assume,

Fig. 3 is a similar view combining the embodiment of my invention shown in Figs. 1 and 2.

My invention comprises, in general, a circuit interrupter 1 having a bridging member

2, a lift rod 3, a crank arm 4 and a biasing member 5 cooperating to operate the bridging member 2 to quickly open the circuit interrupter 1 in a manner to be more fully described hereinafter.

Referring to Fig. 1, the contact members 6, supported from the bushings 7, are connected with each other by means of a bridging member 2. Member 2 is movably mounted on the lift rod 3, being supported thereon by an expanded head 8 at the lower end of the rod. A pressure spring 5 is located on the lift rod 3 between a lug 9 thereon and the bridging member 2. The lift rod 3 is moved downwardly by means of a crank arm 4 mounted on a shaft 11. Upon turning the shaft 11, the lift rod 3 is moved downwardly to compress the spring 5. The engagement between contacts 6 and bar 2 is so tight that considerable force is required to cause their separation. Preferably, this is so great as to hold them together, until the projections at the ends of the member 9 strike against the bridging member 2 to cause it to move out of engagement with the fixed contact members 6. The spring 5 stores energy during this operation and gives it to the bridging member 2 to effect a sudden separation of the contact members.

In the design shown in Fig. 2, the driving crank 12 is loosely mounted on a shaft 11 and there is provided a second crank arm 13 which is rigidly connected to the driving shaft 11 and is loosely or yieldingly connected to the loose crank arm 12 by means of a spring 14. The crank arm 13 is also provided with a projecting lug 15 for the purpose of raising the crank arm 12 during the closing movement of the breaker.

During the opening movement of the breaker, the arm 13 compresses the spring 14 until it strikes against the loose crank arm 12 and causes the bridging member 2 to be disengaged from the fixed contact members 6. As soon as the bridging member 2 has been disengaged from the fixed contact members 6, the stored up energy in the spring 14 will effect a quick separation of the contact members.

In the design shown in Fig. 3, the driving

crank 12, the crank arm 13 and the spring 14 of the Fig. 2 are combined with the lift rod 3, the spring member 5 and the lug 9 of the Fig. 1 to form a structure having still greater mechanical flexibility.

Assuming the circuit interrupter of Fig. 1 to be in its closed position as shown in the drawing, the counter-clockwise movement of the crank arm 4 compresses the spring member 5 to store energy until the lug 9 strikes the bridging member 2. The bridging member 2 is thus moved downwardly and is accelerated by the energy that was stored in the spring member 5, during the initial movement of the arm 4.

It will thus be seen that I am able to obtain a high-speed separation of the contact members 6 without using any greater arc of travel of the crank arm 4 than has been employed heretofore. This is accomplished by utilizing the first portion of the movement of the arm in storing energy in a biasing member to be applied, as an accelerating force, during the last portion of the movement of the bridging member 2. My invention may, therefore, be employed on present apparatus, when an increase in the speed of opening is required, by the mere addition of the biasing structure shown in the figures and described above.

The mode of operation of the modifications shown in Figs. 2 and 3 is so nearly like that of Fig. 1 that separate description thereof is hardly necessary.

I do not wish to be restricted to the specific arrangement of parts herein set forth, as various modifications thereof may be effected without departing from the spirit and scope of my invention. I desire, therefore, that only such limitations shall be imposed as are indicated in the appended claims.

I claim as my invention:

1. In an operating mechanism, a plurality of biasing means stressed in sequence during the initial movement of the said operating mechanism, to store energy that is expended during the final movement of the said mechanism.

2. In an operating mechanism for a circuit interrupter, a plurality of biasing means adapted to store energy on the initial movement of the said operating mechanism, means for producing the initial movement of said operating mechanism, means thereafter to release the circuit interrupter by imparting movement directly from the operating mechanism to the movable element thereof and means to cause said movable element to be accelerated by expenditure of the energy of said energy-storing means.

3. In combination with an operating mechanism for a circuit interrupter that comprises contact members supported by a bridging member, a lift rod for the bridging member loosely connected thereto and to the operating

mechanism, biasing means cooperating with the lift rod and bridging member and with the lift rod and the operating mechanism for storing energy before the bridging member is initially moved directly by the operating mechanism and for expending the said stored energy after said bridging member is moved.

4. A circuit interrupter operating mechanism including a shaft and an actuating arm rotatable therewith, a second arm loosely mounted on the shaft, biasing means between the two arms, a lift rod attached to the last mentioned arm, a bridging member loosely mounted on the lift rod, means on the lift rod for limiting the movement of the bridging member thereon and biasing means between the bridging member and one of the said limiting means.

In testimony whereof, I have hereunto subscribed my name this 6th day of September, 1927.

ALEXANDER KÜHNS.
